DESIGN FOR A BURIAL VAULT

Charles J. King, Galion, Ohio, assignor to The Perfection Steel Body Company, Galion, Ohio,
a corporation

Application July 9, 1934, Serial No. 52,504

Term of patent 14 years

To all whom it may concern:

Be it known that I, CHARLES J. KING, a citizen of the United States, residing at Galion, in the county of Crawford and State of Ohio, have invented a new, original, and ornamental Design for a Burial Vault of which the following is a specification, reference being had to the accompanying drawing, forming a part thereof, in which—

The figure is a perspective view of a burial vault showing my new design.

I claim:—

The ornamental design for a burial vault, substantially as shown.

CHARLES J. KING.
